UNITED STATES PATENT OFFICE

2,478,459

FOLDING MACHINE

Christian Christiansen, Swampscott, Mass., assignor to Rotary Machine Company, Inc., Lynn, Mass., a corporation of Massachusetts

Application November 14, 1947, Serial No. 785,971

5 Claims. (Cl. 12—17)

1

This invention relates to a machine for folding and securing the binding on an insole or for lasting an upper to an insole, and is an improvement on the machine described and claimed in my Patent Number 2,446,043. The nature and objects of the invention will best be understood by reference to the following description together with the accompanying drawings, in which:

Fig. 1 is a view in front elevation of a machine embodying the invention shown in operation;

Fig. 2 is a plan view of said machine also illustrating the operation;

Fig. 3 is a side elevation as viewed from the left of Fig. 1;

Fig. 4 is a detail view of a part of the machine as shown in Fig. 1;

Fig. 5 is a section on line 5—5 of Fig. 2;

Fig. 6 is a detail view showing the end of the folding and holding finger, and

Fig. 7 is a modification of a part of the machine.

In the drawings, a machine frame 1 on a base plate 2 has a support 3 on which a motor 4 is secured as by bolts 5. The drive shaft 6 of the motor supplies power to a system of gears 7 (Fig. 2) which turn a shaft 8 passing through and journaled in a sleeve 9 held in the bracket 10 on the frame. The forward end of the shaft 8 carries a folding wheel 11, which is described more fully later.

A split ring 19 (Fig. 3) is clamped to sleeve 9 and carries a post 20 to which a horizontal arm 21 is fastened. The outer end of arm 21 is clamped to a vertical sleeve or tube 22 through which passes a rod 23. The lower end of rod 23 is provided with a clamping head 24 which holds a rod 25 having a clamping head 25a which holds the stem of a finger 26. The forward end of this finger has a generally spatulate angular end 27; the rearward end of the stem is provided with a connection 28 (Fig. 3) adapted to pass electric current from an extension cord plug 29 to a heating element 30 within the shank of the stem. On the upper end of sleeve 22 is clamped an arm 31 carrying a pin 32 (Fig. 2). A handle 33 clamped to the upper end of rod 23 has a projection 34 secured thereto by a bolt 35. An expansion type spring 36 has one end secured to bolt 35 and the other end held under adjustable tension to pin 32. Projection 34 has a set screw 37 held in position by a lock nut 38. The set screw, under the urge of spring 36, normally bears on post 20.

Finger 26 is held so that its spatulate end is

2

normally positioned adjacent the rim of folding wheel 11 as best shown in Fig. 3. The spacing between the finger and the rim of the wheel is determined by the setting of set screw 37 according to the thickness of material which is to be passed between the end of the finger and the folding wheel. The spring 36, which urges the end of the set screw toward the post 20, also causes the end of the finger to press the material of the work toward and against the rim of the wheel.

The mechanism heretofore described is similar to correspondingly numbered parts in Patent Number 2,446,043, and is not claimed herein. It will be noted, however, that in said application, the wheel 11 had a bevelled portion and preferably a screw-threaded portion, said members cooperating with a flattened portion of the spatulate finger. With the foregoing construction, a supporting roll or wheel was used. The present invention provides a faster working and more simplified mechanism. The wheel 11 now has a bevelled periphery 50, the whole surface of which is provided with threads 51 (Fig. 6). The bevel is preferably between 20 to 30 degrees. The spatulate portion 27 of finger 26 has an inner curved surface 52 which has a concave surface approximately equal in curvature to that of the rim of the folding wheel, and is additionally provided with a small generally triangular tip 53. The tip 53 extends outward substantially at right angles to the flattened portion of the finger, and has its leading edge 54 more sloping (i. e. at a more acute angle to its base) than the trailing edge 55, which is practically perpendicular to the base. The outer part 56 of the finger is given a slight convex curve which aids in rolling the insole over during its passage. The threads have sufficient angularity to the face of the wheel to draw the material and stretch it as it is folded over the tip of the finger. There is a left-hand pitch, as shown in Fig. 6, of about $\frac{1}{4}$ of an inch to the complete turn for a wheel having a diameter of about $5\frac{1}{2}$ inches. In the modification shown in Fig. 7, the folding wheel 11a is also provided with transverse grooves 57, which cross the threads 51 to form separate projections. These interrupted threads are capable of a greater pull on the work, and also serve to retain more of the excess cement, which increases the tackiness of the folding surface.

In operation, the motor 4 is started and turns the folding wheel 11 clockwise as viewed in Fig. 1. Electric current is supplied to resistance unit 30 which heats the finger. An insole A is held with

the surface to be secured uppermost. The insole A has a tape B stitched to one surface of the insole, and this tape has cement along the surface a (Fig. 2) which is to be cemented to the insole. The operator turns the handle 33 counterclockwise as viewed in Fig. 2 to move the finger away from the folding wheel and holds the insole A so that the edge C (Fig. 4) of the insole rests against the tip 53. The upper surface D of the insole rests against the heel 53 of the hooked finger, and the free margin or flap of the tape is passed about the outside of the tip. The tip 53 of the finger then extends as far as possible between the tape and the edge of the insole, and serves to hold the work in place. The inner cement-covered surface of the flap is heated by the hot finger until the cement is softened enough to act as a lubricant and render the tape slippery. The handle is released, causing the free edge of the tape to be pressed between the finger and the bevelled part of the wheel by the pressure applied by the spring. Unless the operator releases the work, the flap is thus held under constant pressure throughout the operation.

The threaded edge of the wheel starts the tape turning about the tip of the finger, grasps the material and stretches it, the slanting threads exerting a continuous pull until the tape is folded past the end of the finger and pressed or "ironed" against the surface of the insole.

Throughout the operation the tip 53 serves as a guide and support for the edge of the insole. Provided the operator pushes the insole through its proper course, the device of the invention pulls the tape tightly about the edge of the insole, heats the cemented tape, stretches it back over the surface of the insole and irons it in place without wrinkles in the tape or gaps in the seal.

I claim:

1. A folding machine having, in combination, a rotatable folding wheel, means for rotating the wheel, heated means adapted to bear against work held between it and the folding wheel during an operating cycle, and an edge supporting

member on said heated means for holding the work in place as it is moved into folding position.

2. A folding machine having, in combination, a rotatable folding wheel, means for rotating the wheel, a heated spatulate finger adapted to bear against work held between it and the folding wheel during an operating cycle, and a projection attached to said finger substantially at right angles to the axis thereof adapted to support the work.

3. A folding machine having, in combination, a rotatable folding wheel, means for rotating the wheel, heated means adapted to bear against work held between it and the folding wheel, a flattened portion on said last named means having a concave area adjacent the folding wheel, and a projection extending outwardly substantially at right angles to said flattened area having a leading and a trailing edge, said projection forming a more acute angle with the flattened portion at its leading edge than at its trailing edge.

4. In the machine of claim 1, in combination, a screw threaded peripheral surface on said folding wheel, and transverse grooves crossing the threads at substantially right angles.

5. A folding machine having, in combination, a rotatable folding wheel, means for rotating the wheel, a heated spatulate finger adapted to bear against work held between it and the folding wheel during an operating cycle, and a generally triangular projection on the end of said finger extending angularly therefrom adapted to support the work.

35 CHRISTIAN CHRISTIANSEN.
